UNITED STATES PATENT OFFICE.

JOHN FRANCIS HENNESSY, OF DULUTH, MINNESOTA.

SCAFFOLD-BRACKET.

1,278,925.

Specification of Letters Patent. Patented Sept. 17, 1918.

Application filed March 2, 1917. Serial No. 151,898.

To all whom it may concern:

Be it known that I, JOHN FRANCIS HENNESSY, of Duluth, St. Louis county, Minnesota, have invented certain new and useful Improvements in Scaffold-Brackets, of which the following is a specification.

The object of my invention is to provide an extremely simple and highly convenient scaffold bracket. To this end I aim to provide a bracket which may be attached to and detached from the wall of a building with very little effort, and which, when attached, will not extend to, or interfere with any work on, the inside of the wall, and will greatly facilitate the work on the outside, by a construction which reduces to a minimum the space of its contact with the wall, and which adapts it to be folded or swung into a non-interfering position while work is being done underneath or about the bracket, and, further, I lessen the expense of constructing scaffolds by simplifying the construction of the bracket and reducing the number of brackets required, while at the same time affording a bracket which will be absolutely safe for staging or scaffolding purposes.

Figure 1, is a side view in elevation of said bracket as it appears when attached to the building, the dotted lines showing the manner in which the brace rod 31, and the rod 35, may be moved or folded together. Fig. 2, is a side view of a so-called extension-piece which may be attached to the main bracket to afford support for a wider platform, the extension-piece being shown in folded position. Fig. 3, is a top view of said extension-piece partially unfolded. Fig. 4, is a view of the main rod equipped with a lever and spring, and of the lower half of the sleeve 8, having a downwardly extending arm. Fig. 5, is a view of the chain and lever attachment of my improved bracket, the use of which will be hereafter explained. Fig. 6, is a view in elevation of the outer end of the outer bearing 6, showing the side-rods of the extension-piece in cross-section; Fig. 7, is an inner-end view of the inner bearing 7; Fig. 8, is an enlarged view of a part of the central portion of the extension-piece; Fig. 9, is an enlarged view of the upper side of the inner end of the extension-piece; Figs. 10 and 11, are side elevations of the outer and inner end portions, respectively, of the horizontal rod and connected parts with the

extension-piece in place in Fig. 11; Fig. 12, shows by dotted lines the manner in which the rod 35 and brace rod may be swung upward so as not to interfere with work below the horizontal rod. Fig. 13, is a view in elevation of a wall of a building showing the holes in which the brackets may be attached. Fig. 14, is a longitudinal section of one form of construction of the inner end of the horizontal rod, Fig. 15, being an end view thereof in which the dotted circle indicates the rod proper and the larger plain circle indicates an end disk or knife, the transverse dotted lines indicating that the intermediate knives 23, go only part way around the rod; Fig. 16 is a view in cross section of said inner end portion and concave member on the line *a a* of Fig. 16^b; Fig. 16^a is a view in cross section on the line *b b* of Fig. 16^b; Fig. 16^b is a side view of said inner end portion and concave member as it appears from the side opposite from that shown in Fig. 18. Fig. 17 is an end view of said rod the dotted lines indicating the rod proper and the larger circle the knife thereon; Fig. 18 is a side view of the inner end portion of the horizontal supporting rod and the bearing or concave member in which it rests, the knives being out of commission. Figs. 19 and 21, are views of opposite sides of said end portion and bearing, the knives being turned into commission, Fig. 20 being an end view and the dotted lines indicating the rod proper. Figs. 22 and 24 are views of a simplified construction of the inner end mechanism of my bracket. Fig. 22^a is a view in cross section on the line *a a* of Fig. 22, and Fig. 23 is an end view of said mechanism. Fig. 25 is a side view of a modification of the concave member and of the horizontal rod. Fig. 25^a is a side view of a short knife-bearing rod used in said construction. Fig. 26 is a sectional view of the concave member shown in Fig. 25^a, and the rod and lever for turning it. Fig. 27 is a side view, and Fig. 28 an end view, of the concave member with a ring around its end. Fig. 29 is a view of the inner end portion of the horizontal rod threaded instead of being provided with knives.

As shown in Fig. 1, one part of my improved bracket has the horizontally projecting main rod 1, the inner end of which is adapted to be inserted in a hole 2, preferably

- in the studding 3, of the wall 4. One important feature of my invention is that this rod has lateral projections, preferably disks or knives 5, on the inner end portion thereof, by means of which it may be firmly attached in a wall, and that when so attached it does not extend entirely through the wall 4. (See Figs. 1 and 4.) These projections may be made and operated in several different ways.
- 10 For example, I may simply thread the inner end portion of said rod with one or more spiral ribs, as in Fig. 29, and, by turning it as hereinafter explained, screw said rod into a hole in the wall made somewhat smaller than the diameter of the threaded end of said rod; but to avoid the necessity of turning the rod a number of times in order to attach it, or any other undesirable features that might be connected with this method of attachment, I may construct the inner end mechanism of said rod in certain other ways shown in detail by the drawings.
- 15 For the present I adopt, as the most simple and convenient means of attaching said rod, the construction shown by Figs. 18 to 24, particularly in Figs. 22 and 24. By reference to Figs. 22 and 24, it will be seen that the inner end portion of the main rod 1, is provided with the laterally projecting knives or blades 5, preferably curved or crescent shape in plan view and triangular in cross section, these blades being disposed parallel to one another along the rod near the end thereof and somewhat obliquely to its axis. (See Fig. 23). Said main rod 1, is adapted to turn in the bearings 6 and 7, (Fig. 1) and in the box or sleeve 8, composed of an upper half 9, and a lower half 10, held together by the bolts 11 (see Fig. 24). When the rod is attached to a building, the inner end of the upper half 9, of this sleeve ends at the wall 4, but the lower half 10, of the sleeve extends inward to a point in close proximity to the knives 5, and forms a half-box or concave member 12, for the shank 13, of the main rod 1. This rod 1, may be turned either by means of the lever 14, rigidly attached thereto, as in Figs. 4 and 18, or said lever 14, may be dispensed with and said rod may simply be made with flat sides at the point 15, where said lever might be attached, (see Fig. 1) and the rod may then be turned by means of a wrench. If a lever is used, it may be locked in inoperative position, as shown in Fig. 18, by the spring 17, attached to said lever, or by suitable means, to the arm 18, which extends downward from and is a part of the lower half of the sleeve 8. The diameter of the inner end portion of said main rod 1, with the thickness of the concave member added thereto, is preferably somewhat smaller than that of a hole which may be bored in the edge of the studding, so as to allow of easy insertion of said rod and concave member
- in said hole. When the main rod 1, is in the position shown at Figs. 4, or 18, or 24, the lever 14, if present, points upward and the knives rest in the half-nut 12 but when turned in said bearings 6 and 7 and in said sleeve 8, one-half of a revolution, more or less, by any of the means just described, the concave member 12, will resist the downward pressure of the shank 13, of said main rod 1, caused by the eccentric knives coming in contact with the upper part of the hole 2, and this will cause the said knives 5, to cut themselves firmly into the wood of the studding, as shown in Figs. 1 and 22. To give said knives 5, a firm hold in the wood, and thus increase their resisting capacity when pressure or tension is exerted on the main rod 1, away from the wall 4, said knives 5, are made triangular in cross-section, and their outer sides 19, are at right angles with the rod, so that as the knives enter the wood in the manner described the wood will be squeezed tightly between them and downward against the body of the rod 1. When the rod and knives are in the wall and in the position shown in Figs. 19, 21 and 22, they cannot be drawn away from the wall. They may, however, be easily released by simply turning the rod 1, back to its former position shown in Figs. 4, 18 and 24. The inner end of the upper half 9, of the sleeve 8, is made sufficiently thick to serve as a block or barrier to prevent the rod or sleeve from being pushed too far into the hole 2. The sleeve 8, may be made any desired length, but the longer it is made, and the greater the distance between the wall 4, and the lever 14, the thicker may the wall be built outward from the studding without interference by the bracket. The sleeve 8, is kept from sliding outward on the rod 1, by its outer end coming in contact with the lever 14, if used, or by an increased thickness or collar 20, at the point 15, (Fig. 1).
- 20 Instead of extending the concave member 12, inward only to the point shown in Figs. 22 and 24, and using only circular knives, the concave member 12, may be extended nearly to the inner end of the rod as shown in Figs. 18 and 19, and in such case it is provided with the cuts or slits 21, extending transversely from and through one of its edges and sides to a point half-way around or more the concave member 12, said member then having somewhat the appearance of a concave comb. When such a bearing is used, only a few knives 22, near the extreme end of the main rod 1, which are shaped the same as the knives 5, in Figs. 22 and 24, will be made entirely circular in plan, and the rest of the knives 23, will extend only part way around the rod. (See Figs. 19, 20 and 21.) The centers of all the circles of which the knives form a part are eccentric with respect to the axis of the rod 1, so

that the knives may be housed in the slits of the concave member 12; or may through a half revolution of the rod 1 be forced into the upper part of the hole in the studding. 5 By this construction the number of knives may be greatly increased if found desirable, and when the knives are locked in inoperative position by means of the lever 14 and spring 17, and arm 18, they will be protected 10 from becoming dulled or broken by collision with hard substances when the bracket is carried about or stored. Little dents or niches 24 may be provided on the unslotted edge of the bearing to protect the edges of 15 the knives in case the rod should be turned too far around toward said unslotted edge. If desired I may place a ring or band 25, as in Figs. 27 and 28, at or near the end of the bearing and around the bearing and rod 20 to keep them from separating.

Instead of having the knives positioned on the main rod as above described, I may, if desired, make the inner end portion of said main rod concave, or channel-shaped in cross section, and place in the concave or trough thus formed the short knife-bearing rod 26, (see Figs. 25 and 26) which may be turned by means of the lever or other projection 27, placed at its outer end, and preferably placed 30 as shown in Fig. 26, in order to secure as much as a half turn of the rod and knives 5.

At the outer end of the rod 1, (Figs. 1 and 10) is the end-piece or outer bearing 6, in which the rod 1, may revolve, and which may 35 also be turned on said rod. It is held in position by the nut 28, and by a small shoulder 29, on the rod 1. If desired this end-piece or bearing 6, may be provided with the springs 30, (Fig. 6) for locking the rods in 40 folded position as shown by dotted lines in Fig. 1. Between the bearings 6 and 7, the rod 1, is preferably made hollow, to secure lightness, and it may also be made with a rough, corrugated or spiked surface to keep 45 the planks from sliding off. Pivotal connected to the bearing 6, is the brace rod 31, which is preferably made double, that is, made of two parallel rods, which are joined 50 at the ends, their upper ends being merged into a single member for pivotal connection with said bearing 6. Each of these parallel rods is made with a hump or heel 32, the under side 33 of which may be made somewhat concave, and the lower end of the brace rod 55 31, is provided with a toe or knob 34, which holds the rods in parallel alinement and bears against the wall 4, when the bracket is in use. The inner bearing 7, like the outer bearing 6, is adapted to turn on the rod 1. 60 Pivotal connected to the bearing 7, is the tie-rod 35, which extends downward between the parallel rods which make up the brace rod 31, and is threaded at its lower end and provided with the oblong nut or barrel 36, 65 adapted to be threaded upward or down-

ward as desired, and which when threaded against the heels 32, of the double brace-rod 31, affords a prop for the lower part of said brace-rod, so that this in turn can support the outer end of the main rod 1. In attaching the bracket to the building it is only necessary to bore a hole in the studding, either from the inside or the outside of the wall as may be found most convenient, and insert therein the inner end portion of the horizontal main rod 1, turning said main rod by any of the means above described to enable the knives or other projections to cut themselves into the wood of the studding, and screwing or threading the barrel 36, upward tightly against the heels 32, of the brace-rod 31. In brick veneer work or any work where any material of considerable thickness is placed against the outside of the wall, the barrel 36, may be lowered and the 70 brace rod 31, thrown outward, as shown by the dotted lines in Fig. 1, and thereupon the connection may be again tightened. Of course I may use other means for adjusting the lower portions of said brace-rod and tie-rod with reference to each other, such as holes spaced along said rods and a pin for inserting therein. It will be noticed that neither the brace-rod nor the tie-rod is attached in any manner to the wall, the lower 75 end of the brace rod merely bearing against the wall, and the tie-rod 35, being positioned outward of and free from the wall; but when combined as just described these rods form a rigid and absolute support for the horizontal 80 main rod 1, and any planks or platform that may be placed thereon, and also leave room for any projections, ornamental or otherwise, that may exist on the wall, such as the belt course shown in Fig. 1. If for 85 any reason it is desired to move these downwardly extending rods entirely away from beneath the main rod, the barrel 36 may be loosened and the rods may then simply be swung sidewise, around and upward as indicated by the dotted lines at Fig. 12, where 90 they are shown resting against the wall and on a plank 39.

Where it is desired to use a wider platform, the extension-piece shown at Figs. 2 115 and 3, may be attached to the bracket. Referring to Fig. 3, it will be seen that this extension-piece consists of two parallel rods fastened together by the braces 40 which are placed only at the outer and intermediate 120 portions of said rods so that the rods will be free of each other along their inner half portions. This extension-piece may be attached by pushing the end of each of its side rods inward into the eyes or openings 41, in bearing 7, formed by the lugs 42 and 43, (see Fig. 7) and the inner end of the extension-piece cannot then move upward or sidewise. To prevent the extension-piece from moving 125 outward it is provided with the laterally 130

yielding springs 44, (Figs. 3 and 9) which will automatically lock, one on each side, over the lug 42, when the extension-piece is pushed inward, and the center portion of the 5 said extension-piece will then rest on the lugs 45, on each side of the bearing 6, and the end 46, of the main rod 1, will then engage a hole in the brace 40, shown by dotted lines in Fig. 8, and when in this position the extension-piece cannot rise or fall at either end. 10 Its upper line is preferably placed somewhat below the level of the upper line of the main rod 1, so that it may be pushed into position on the lugs while there are planks on the 15 main rod 1. Said extension-piece is also provided with the braces 47, which are pivotally connected with the inner portion of said extension-piece and are adapted to be spread or folded together as desired, and 20 which when spread will prevent the staging from moving sidewise. Auxiliary braces 48, are pivotally attached to said main braces and slide in the slots 49, in the operation of folding or extending said braces. The 25 braces are made rigid in extended position by means of the thumb-screws 50. (See Fig. 2).

The expense and trouble of constructing scaffolds are greatly lessened by the use of 30 this bracket, not only by its simple construction and adaptability for quick and easy attachment and detachment, but also by reason of the fact that by the use of the chain and lever attachment hereinafter described only 35 one extra bracket, and no ladder, is necessary, where it is desired to move the scaffold, from a lower to a higher level or vice versa. For example, referring to Fig. 13, we will 40 suppose that the scaffold is supported by the brackets at 51, 52, 53 and 54, and it is desired to raise it. The extra bracket may be attached at the point 55, and the upper end of the chain and lever attachment shown at Fig. 5, may then be hooked thereon. The 45 pole 56, (Fig. 5) has permanently attached to it at 57, a chain 58, but the chain 59, slips over its end, so that the plank 60, may be held on the pole 56, between the chains 58 and 59, and at the same time be held steady 50 by the end of the pole coming in contact with the wall 4. Now, by pressing downward the outer end of the lever 61, and hooking it to the chain 62, by means of the hook 63, the chains will be tightened so as to raise 55 the plank 60, to the position shown by the dotted lines, and the bracket at 51, may then be readily removed and attached at the point 64, (Fig. 13) and a plank may then be laid upon the two upper brackets. A man standing 60 on said plank may then take hold of the chain and lever attachment by the hand-hold 65 (Fig. 5) and, walking from the point 55 to the point 64, he may carry the outer end of the plank 60, by means of said 65 chain and lever attachment, to a point di-

rectly beneath the bracket at 64, and attach the chain and attachment to said bracket at 64, while a man below carries the other end, from bracket at 52 to bracket at 53. Standing on the suspended end of the plank thus 70 carried, the man below may now remove the free planks from bracket at 52, and detach said bracket, and transfer it to point 66, and hand the man above a plank for laying between the points 64 and 66, on which the man 75 above may walk and again carry the end of the plank 60, by means of the chain and lever attachment for suspending from the point 66, while the man below carries the other end to the bracket at 54, walks on the suspended plank, and detaches the bracket at 53, for attachment at the point 67, and transfers planks to the man above for laying between the points 66 and 67, to complete the 80 upper scaffold; and the plank resting with 85 one end on the bracket at 54, and the other end of which is suspended from the point 66, may be used as a lower scaffold or the chain may be unhooked from the point 66, and the bracket at 54, detached and the 90 lower scaffold thus entirely removed. In case the bracket at 54, cannot be reached from the ground or other level, another chain and lever attachment may be suspended from the bracket at 67, to support the end of 95 the plank resting on bracket 54, and after the bracket at 54 has been detached, the man below may hand it to the man above and then climb up to the bracket at 67, and pull the plank up at that end by means of said 100 attachment, while the other man pulls up the other end by means of the attachment at that end, and the staging so raised may then be again raised in the same manner if desired. 105

In some cases it might be desirable to pivotally connect the brace-rod 31, and the tie-rod 35, directly to the main rod 1, at or near the outer and inner ends respectively of said main rod 1, instead of connecting 110 them to the members 6 and 7 respectively.

What I claim is:

1. A scaffold bracket comprising a plurality of bearings, a rotatable supporting rod journaled in said bearings, a brace rod 115 connected to one of said bearings, a tie rod connected to one of said bearings and to said brace rod, and means on said supporting rod for securing said supporting rod in place in a wall by motion around its longitudinal axis after inserting an end portion 120 of said supporting rod into a hole in said wall.

2. A scaffold bracket comprising a plurality of bearings, a rotatable supporting rod journaled in said bearings, a brace rod connected to one of said bearings, a tie rod connected to one of said bearings and the said brace rod, means on said supporting rod for securing said supporting rod in place in a 130

wall by motion around its longitudinal axis after inserting an end portion of said supporting rod into a hole in said wall, and means for extending a support afforded by 5 said supporting rod, consisting of lugs on said bearings, parallel bars slidably mounted on said lugs and extending outwardly beyond the outer end of said supporting rod, 10 braces for holding said bars in parallel alignment, and braces for holding said scaffold and said bars against laterally swaying movement, substantially as described.

3. In connection with a scaffold bracket, an extension piece comprising parallel bars

spaced free of each other along their inner 15 half portions, braces rigidly secured between the outer and between the intermediate portions of said bars, and means for holding said extension piece against laterally swaying movement, consisting of main braces 20 pivotally connected to the inner end portions of said bars and adapted to engage a wall, and auxiliary braces pivotally connected to the intermediate portions of said main braces and slidably connected to the intermediate portions of said bars.

JOHN FRANCIS HENNESSY.
